UNITED STATES PATENT OFFICE.

ARTHUR MIDDLETON ROSE, OF YONKERS, NEW YORK.

DESIGN FOR CARPET.

SPECIFICATION forming part of Design No. 26,056, dated September 15, 1896.

Application filed August 11, 1896. Serial No. 602,455. Term of patent 3 $\frac{1}{2}$ years.

To all whom it may concern:

Be it known that I, ARTHUR MIDDLETON ROSE, a citizen of the United States, residing at the city of Yonkers, in the county of Westchester and State of New York, have invented and produced a new and original Design for a Carpet or other Fabric, of which the following is a specification, reference being had more particularly to the accompanying drawing, illustrating the same and forming part hereof.

The leading feature of my design consists in rococo ornaments associated with conventional flowers.

¹⁵ a is the body, b the border, and ab the complete carpet. Upon a suitable background appear the rococo ornaments c and the conventional flowers d.

²⁰ The design of my invention will be best understood by reference to the drawing, and it may be applied to or wrought in Brussels, velvet, Wilton, ingrain, or other carpeting in such colors or combinations of colors as may be desired.

What I claim as my invention, and desire to secure by Letters Patent, is—

1. In a design for a carpet, the body a, substantially as shown.
2. In a design for a carpet, the border b, substantially as shown.

3. The design for a carpet consisting of the body a, and border b, substantially as shown.

In testimony whereof I have hereunto signed my name in the presence of two witnesses.

ARTHUR MIDDLETON ROSE.
